UNITED STATES PATENT OFFICE

170,102

ADDING MACHINE

George W. Walker, Detroit, Mich., assignor to
Burroughs Adding Machine Company, Detroit,
Mich., a corporation of Michigan

Application November 5, 1952, Serial No. 22,127

Term of patent 14 years

(Cl. D64—11)

To all whom it may concern:

Be it known that I, George W. Walker, a citizen of the United States, residing at Detroit, county of Wayne, State of Michigan, have invented a new, original, and ornamental Design for an Adding Machine, of which the following is a specification, reference being had to the accompanying drawings forming a part thereof.

In the drawings:

Figure 1 is a front elevational view of an adding machine, showing my new design;

Figure 2 is a front perspective view thereof;

Figure 3 is a rear elevational view thereof; and

Figure 4 is a rear perspective view thereof.

I claim:

The ornamental design for an adding machine, substantially as shown.

GEORGE W. WALKER.
